TYPEWRITER COMPANY, OF NEW YORK, N. Y., A CORPORATION OF DELAWARE.

TYPE-WRITING MACHINE.

1,175,886.

Specification of Letters Patent. Patented Mar. 14, 1916.

Application filed June 16, 1915. Serial No. 34,327.

To all whom it may concern:

Be it known that I, JOHN C. McLAUGHLIN, a citizen of the United States, residing in East Orange, in the county of Essex and State of New Jersey, have invented certain new and useful Improvements in Type-Writing Machines, of which the following is a specification.

This invention relates to typewriting machines, and one of its principal features is the provision of means for controlling the heaviness or faintness of the ink impressions made through the usual inking ribbon.

The invention is particularly intended for use in connection with the writing of addresses upon circulars, such as are usually printed through an inking ribbon, as for instance, circulars produced on the well-known multigraph machine. In printing said circulars through an ink ribbon, it is found that the ribbon of the printing machine wears rapidly, and hence the impressions become fainter and fainter, although still legible and satisfactory. The subsequent writing of the necessary addresses upon the printed circulars presents a difficulty, because the typewriter ribbon, although originally corresponding in heaviness of inking with the ribbon of the multigraph machine, does not wear out so rapidly, so that the typewriter ribbon will be still fresh even after writing in the addresses on a large number of multigraph circulars; whereas the multigraph printing will become comparatively faint, for reasons above given. The first addresses will correspond so closely to the printing upon the circular that the addressing and printing will seem to have been done upon a single typewriting machine; but after a while, the printing upon the circulars becomes faint, while the typewriting of the addresses remains fresh and strong, thus calling the attention of the recipient of the circular to the fact that it is merely a circular, which is an objection. In overcoming this difficulty, the typewriting machine is provided with means for controlling the ink impressions of the types, so that the ribbon can be caused to give either a strong or faint impression, even though the ribbon is unworn. In controlling these ink impressions, the type-bars are arrested when the types are close to the platen, so that it is necessary for the types to spring in order to reach the platen: the arresting points of the type-bars

being near their pivot ends, and the type-bars being usually resilient enough to spring; the blow of the type being comparable to the action of snapping a whip. The platen is made adjustable forwardly and backwardly by means of a device which permits very minute adjustments; and by relying at one point upon the arrest of the springy swinging type-bars, and at another point upon the minute adjustment of the platen, it is found that the ink impressions can be absolutely controlled, so that the operator can at all times make the addresses correspond precisely with the inking of the body of the circular, whether the latter is strongly or faintly printed.

In carrying out the invention, I employ the well-known Underwood typewriting machine, in which it is customary to arrest the hub portions of the swinging type-bars or hammers, when the types are close to the platen, and in which it is customary to shift the platen up and down for writing upper and lower case letters; and I effect a fine forward and rearward adjustment of the printing position of the platen while in the limited field through which the type-bars can spring, by mounting upon eccentrics, the rock shaft which is used in shifting the platen up and down. By turning the eccentrics the platen may be drawn rearwardly or forwardly until the ink impressions correspond exactly with the printing upon the multigraph circular.

The device is also useful when it is desired to make a correction on a typewritten page which may have been written either faintly or heavily; as the platen may be adjusted so that the work of the ribbon will be made to correspond with the work upon the typewritten page, so that when the blanks are filled in, the ink impressions will be all of the same tone. This is an advantage, not only in typewritten work, but also in filling in blanks on multigraph work.

Other features and advantages will hereinafter appear.

In the accompanying drawings which illustrate the invention as applied to an Underwood typewriting machine, Figure 1 is a perspective view of the platen, and means for adjusting it forwardly and rearwardly. Fig. 2 is a fragmentary end elevation view, partly in section, showing the platen adjusted rearwardly for producing

comparatively faint ink impressions. Fig. 3 is a perspective view, showing a portion of the carriage frame, a shiftable plate forming part of the platen adjusting means, and 5 an intermediate plate, the parts being shown disassembled. Fig. 4 is a fragmentary view of the platen frame and a link connecting it to the adjusting plate of Fig. 3. Fig. 5 is a view similar to Fig. 2, but with the 10 platen in upper case position and adjusted forwardly for producing comparatively heavy ink impressions. Fig. 6 is a fragmentary sectional view, showing one of the eccentric bushings and gearing for operating 15 the same. Fig. 7 is an elevation view, similar to Fig. 5, but showing more of the typewriter mechanism, and also showing the platen in lower case position.

The type-bars 10 provided with upper and 20 lower case types 11 and 12, are mounted on a fulcrum rod 13 to swing upwardly and rearwardly to printing position at the front face of the platen 14. The type-bars are actuated by keys 15, on key levers 16 fulcrumed at 17 and connected through bell-crank 18 to the type-bars. The platen has an axle 19, journaled to the platen frame 20, and may be rotated either by hand wheels 21 or by the usual line-spacing mechanism, 25 not shown. The platen frame 20 is mounted to shift up and down to upper and lower case positions in the carriage 22.

The carriage is mounted to travel on front and rear guide rails 23 and 24, secured to 30 the machine frame 25, and may be driven by the usual spring motor, not shown. The letter-feed travel of the carriage may be controlled by the usual mechanism comprising escapement dogs 26 on a rocker 27, actuated 35 by a universal bar 28, which lies in the path of shoulders 29 on the type-bars, so that at each type stroke the dog rocker 27 is actuated. The dogs 26 coöperate with the escapement wheel 30, driven by a pinion 31 40 running in mesh with a carriage rack 32.

The platen may be shifted to upper case position by means of shift keys 33 on shift key levers 34, fulcrumed at 17, and operable to swing the platen-shifting frame 35, which 45 frame comprises a rock shaft 36 forming the fulcrum of said frame, and a shift rail 37 on which runs a roll 38 on the platen frame. The platen may thus be shifted from the lower case position, Fig. 7, to upper case 50 position, Fig. 5. The platen is partly supported and guided and held against displacement in a forward or rearward direction by a platen-lifting frame comprising rock arms 39, fixed to a rock shaft 40 and 55 projecting forwardly therefrom, the forward ends of said arms provided with hooks forming bearings in which are seated studs 41, on the platen frame. An adjustable platen-lifting spring 42 having its tension 60 rotatively applied to the shaft 40, partly

counter-balances the weight of the platen frame and parts supported thereby.

The type-bars, as they swing to printing position, are brought against a stop 43, which may be formed on a type-bar segment 44, on which the type-bars are mounted, said segment being fixed to the machine frame. The stop 43 is located adjacent to the type-bar fulcrum rod 13, or nearer to said rod than to the types, and is so positioned that the type-bars normally strike the stop just before the types reach the printing position against the platen, whereby the type-bars are arrested and the types caused to complete their printing stroke by momentum; the type-bars being made of resilient or springy material to permit the springing of the types to printing position.

In accordance with the present invention, provision is made for a fine adjustment of 85 the platen forwardly and rearwardly within the printing range of the types, in order to vary the tone of the ink impressions produced by the types striking through the ribbon 45, so that without changing the ribbon, 90 the impressions may be varied at will through imperceptible degrees from a comparatively thin or faint impression to a strong or dense impression. The ribbon may be fed in the usual manner, and vibrated at each type stroke over the printing point between the type guide 46 and the platen, by the usual ribbon-vibrating mechanism, not shown. The ink impressions will be comparatively heavy or light in accordance with the adjustment of the platen forwardly or rearwardly, as just referred to. Such adjustment of the platen is effected by the following means: The rock shaft 40 is journaled in eccentric bushings 47, which, in turn, are mounted for rotative adjustment in bearings 48, on the carriage frame. It will thus be seen that by rotating the bushings 47 in their bearings 48, the rock shaft 40 carrying the rock arms 39, may be adjusted forwardly and rearwardly, effecting a corresponding adjustment of the platen frame and platen. The eccentric bushings are rotated to effect such adjustment by pinions 49, fixed to the bushings and rotated 105 by segmental racks or gears 50. The gears 50 are fixed to a rock shaft 51 journaled in brackets 52 and 53, fixed to the carriage frame. The shaft 51 is rocked by means of a crank 54, fixed thereto, and provided with a handle 55. The crank 54 may be formed with a pointer 56, working over a graduated scale 57, to indicate the position of adjustment. Said scale may be formed on a plate 58 having a fixed connection with the bracket 52, said plate provided with a series of recesses or depressions 59, in any one of which may seat a spring-actuated detent 60, (Fig. 6) carried by the arm 54. The detent 60 is shown as a ball, actuated by a spring 110

115 120 125 130

61, in the handle 55. The throw of the handle may be limited by stops 62 on the plate 58. When the handle 55 is moved rearwardly, to the Fig. 7 position, the platen 5 is adjusted forwardly, to such a position that the types are brought very close to or in contact with the platen by the time the type-bars strike the stop 43, so that a comparatively heavy ink impression is produced 10 by the type striking through the ribbon. As the handle 55 is moved forwardly the platen is carried rearwardly, so that the distance the types have to spring forward to the printing point after the type-bars strike the 15 stop 43, is increased and a correspondingly light or faint impression is produced. It will thus be seen that provision is made for a fine adjustment of the platen within the striking range of the types.

20 In the Underwood machine it is customary to provide a link, such as the link 74, Fig. 7, connecting the carriage and platen frame, to brace the platen frame and hold it against tilting. In the present invention the link 74 is not pivoted directly to the carriage frame, but to a shifting plate 63, adjustable forwardly and rearwardly with the platen by the following means: The plate 63 is actuated by a pin 30 64, forming an extension of the stud 41 at the right-hand end of the platen frame, the pin 64 working idly in a vertical slot 65, in said plate, as the platen is shifted up and down, but moving the plate with the platen 35 frame as the latter is adjusted horizontally. Said plate is supported and guided by a plate 66, fixed to the carriage frame 22, as by means of screws 67 and 68. The plate 63 is formed with slots 69 and 70, through 40 which the screws 67, 68 extend. A pin 71 on the plate 63 extends through registered openings 72, 73, in the plate 66 and carriage frame. The pin 71 forms a fulcrum for the link 74, the forward end of said link being 45 connected by a pivot pin 75 to the platen frame 20. The link 74, which helps to steady the platen and prevent it from tilting about its bearings in the rock arms 39, is caused through the connections just de- 50 scribed, to shift forwardly and rearwardly with the arms 39.

Variations may be resorted to within the scope of the invention, and portions of the improvements may be used without others.

55 Having thus described my invention, I claim:

1. In a typewriting machine, the combination, with a platen, and key-operated swinging type-bars whose types strike 60 through an ink-ribbon against the front side of said platen; of a rigidly-mounted, stationary stop arranged to engage the type-bars near their pivot ends before their type-carrying ends reach the platen; and a 65 device connected to said platen to shift the

same horizontally in a plane parallel to itself away from the printing plane of the types, thereby to gradually render the type-impressions fainter as the platen moves farther away from said printing plane. 70

2. In a typewriting machine, the combination, with a platen, and key-operated, swinging type-bars whose types strike through an ink-ribbon against the front side of said platen; of a rigidly-mounted, 75 stationary stop arranged to engage the type-bars near their pivot ends before their type-carrying ends reach the platen; and a device connected to said platen to shift the same horizontally in a plane parallel to itself 80 away from the printing plane of the types, thereby to gradually render the type-impressions fainter as the platen moves farther away from said printing plane, said device comprising a shaft arranged behind and parallel with said platen and connected at opposite ends therewith, a pair of eccentric bushings wherein said shaft is journaled, and means for rotating both bushings equally and concurrently in the same direction, 85 thereby to shift said shaft laterally rearward in a plane parallel to itself.

3. In a typewriting machine, the combination, with a platen, and key-operated, swinging type-bars whose types strike 90 through an ink-ribbon against the front side of said platen; of a rigidly-mounted, stationary stop arranged to engage the type-bars near their pivot ends before their type-carrying ends reach the platen; and a device 95 connected to said platen to shift the same horizontally in a plane parallel to itself away from the printing plane of the types, thereby to gradually render the type-impressions fainter as the platen moves farther 100 away from said printing plane, said device comprising a shaft arranged behind and parallel with said platen and connected at opposite ends therewith, a shaft arranged behind and parallel with the first-named shaft, means for rotating the second-named shaft, and connections between the adjacent 105 ends of said shafts for shifting said first-named shaft laterally rearward in a plane parallel to itself when said second-named 110 shaft is rotated.

4. In a typewriting machine, the combination, with a platen, and key-operated, swinging type-bars whose types strike 115 through an ink-ribbon against the front side of said platen; of a rigidly-mounted, stationary stop arranged to engage the type-bars near their pivot ends before their type-carrying ends reach the platen; and a device 120 connected to said platen to shift the same horizontally in a plane parallel to itself away from the printing plane of the types, thereby to gradually render the type-impressions fainter as the platen moves farther 125 away from said printing plane, said device 130

- comprising a shaft arranged behind and parallel with said platen and connected at opposite ends therewith, a pair of eccentric bushings wherein said shaft is journaled, a shaft arranged behind and parallel with the first-named shaft, means for rotating the second-named shaft, and connections between said bushings and the adjacent portions of said second-named shaft for rotating both bushings equally and concurrently in the same direction when said second-named shaft is rotated, thereby to shift the first-named shaft laterally rearward in a plane parallel to itself.
15. In a typewriting machine, the combination, with a platen, and key-operated, swinging type-bars whose types strike through an ink-ribbon against the front side of said platen; of a rigidly-mounted, stationary stop arranged to engage the type-bars near their pivot ends before their type-carrying ends reach the platen; and a device connected to said platen to shift the same horizontally in a plane parallel to itself away from the printing plane of the types, thereby to gradually render the type-impressions fainter as the platen moves farther away from said printing plane, said device comprising a shaft arranged behind and parallel with the opposite ends of said shaft and arranged for equal and concurrent operation in the same direction, to shift said shaft laterally rearward in a plane parallel to itself.
20. In a typewriting machine, the combination, with a platen, and key-operated, swinging type-bars whose types strike through an ink-ribbon against the front side of the platen; of a rigidly-mounted, stationary stop arranged to engage the type-bars near their pivot ends before their type-carrying ends reach the platen; and means connected with said platen, and means connected with the opposite ends of said shaft and arranged for equal and concurrent operation in the same direction, to shift said shaft laterally rearward in a plane parallel to itself.
25. In a typewriting machine, the combination, with a platen, and key-operated, swinging type-bars whose types strike through an ink-ribbon against the front side of the platen; of a rigidly-mounted, stationary stop arranged to engage the type-bars near their pivot ends before their type-carrying ends reach the platen; a device connected to shift said platen horizontally in a plane parallel to itself away from the printing plane of the types, thereby to gradually render the type-impressions fainter as the platen moves farther away from said printing plane; and a detent associated with said device for holding the same at short intervals throughout its range of movement, to retain said platen in adjusted position.
30. In a typewriting machine, the combination, with a platen, and key-operated, swinging type-bars whose types strike through an ink-ribbon against the front side of the platen; of a rigidly-mounted, stationary stop arranged to engage the type-bars near their pivot ends before their type-carrying ends reach the platen; a device connected to shift said platen horizontally in a plane parallel to itself away from the printing plane of the types, thereby to gradually render the type-impressions fainter as the platen moves farther away from said printing plane; and a device comprising an operating shaft and a

handle therefor; and a detent associated with said handle for holding the same at short intervals throughout its range of movement, to retain said platen in adjusted position.

8. In a typewriting machine, the combination, with a platen, and key-operated, swinging type-bars whose types strike through an ink-ribbon against the front side of said platen; of a rigidly-mounted, stationary stop arranged to engage the type-bars near their pivot ends before their type-carrying ends reach the platen; and a device connected to said platen to shift the same horizontally in a plane parallel to itself away from the printing plane of the types, thereby to gradually render the type-impressions fainter as the platen moves farther away from said printing plane, said device comprising a shaft arranged behind and parallel with said platen and connected at opposite ends therewith, and an eccentric mechanism connected with said shaft for shifting it laterally rearward in a plane parallel to itself.

9. In a typewriting machine, the combination with key-operated swinging type-bars, of a carriage, a platen thereon shiftable to upper and lower case positions, type-impression-controlling means including stopping means engaged by the type-bars near their pivot ends to arrest the bars when their types are close to the platen, whereby the type-bars must spring to strike the platen, and means for effecting fine adjustment of the platen within the striking range of the type-bars to render the ink type-impressions fainter or stronger at will, said adjusting means comprising a rock shaft, rock arms connecting said shaft to the platen, eccentric bushings in which said shaft is mounted to rock, said bushings journaled in the carriage frame, a second rock shaft journaled in the carriage frame, intermeshing gears on said rock shafts, an operating crank connected to said second shaft, a pointer carried by the crank, and an index over which said pointer works to indicate the position of adjustment.

10. In a typewriting machine, the combination with a platen frame and a platen journaled thereon, of a carriage on which the platen frame is mounted to shift up and down to upper and lower case positions, key-operated type-bars mounted to swing upwardly and rearwardly to printing position at the platen, a stop to arrest the type-bars when the types are close to the platen, whereby the type-bars must spring to strike the platen, means to adjust the platen toward and from the type-bars to render the inked type-impressions stronger or fainter at will, said adjusting means comprising eccentric bushings journaled in the carriage frame, a platen-lifting frame comprising a

rock shaft journaled in said bushings and rock arms fixed to the ends of said shaft and connected to the platen frame, whereby said shaft is rocked as the platen is shifted up and down, a second rock shaft journaled in the carriage frame, intermeshing gears connected respectively to said bushings and to said second rock shaft, and an operating crank connected to said second rock shaft for rotating said bushings, and thereby by adjusting the platen forwardly or rearwardly within the printing range of the types to render the type-impressions fainter or stronger at will.

11. In a typewriting machine, the combination with a platen frame and a platen journaled thereon, of a carriage on which the platen frame is mounted to shift up and down to upper and lower case positions, key-operated type-bars mounted to swing upwardly and rearwardly to printing position at the platen, a stop to arrest the type-bars when the types are close to the platen, whereby the type-bars must spring to strike the platen, means to adjust the platen toward and from the type-bars to render the inked type-impressions stronger or fainter at will, said adjusting means comprising eccentric bushings journaled in the carriage frame, a platen-lifting frame comprising a rock shaft journaled in said bushings and rock arms fixed to the ends of said shaft and connected to the platen frame, whereby said shaft is rocked as the platen is shifted up and down, a second rock shaft journaled in the carriage frame, intermeshing gears connected respectively to said bushings and to said second rock shaft, and an operating crank connected to said second rock shaft for rotating said bushings, and thereby adjusting the platen forwardly or rearwardly within the printing range of the types to render the type-impressions fainter or stronger at will, a plate shiftably mounted on the carriage frame and connected to one of said rock arms to be shifted forwardly and rearwardly with the platen frame, and a link connecting said shifting plate with the platen frame to prevent tilting of the platen.

12. In a typewriting machine, the combination, with key-operated, swinging type-bars; of a carriage; a platen thereon; type-impressions controlling means including a stop engaged by the type-bars near their pivot ends to arrest the bars when their type-carrying ends are close to the platen, whereby said type-carrying ends are caused to spring toward the platen so as to strike the same; and means for effecting fine adjustment of the platen within the striking range of the type-bars, to render the type-impressions fainter or stronger at will, said adjusting means comprising a rock shaft, rock arms connecting said shaft to the platen, eccentric bushings in which said shaft is allowed to rock, said bushings journaled in the carriage frame, a second rock shaft journaled in said carriage frame, intermeshing gears on said rock shafts, and an operating member connected to the second-named rock shaft.

13. In a typewriting machine, in which the types are arranged to strike against the front face of the platen, the combination with a carriage and a platen frame and platen mounted thereon to shift up and down to upper and lower case positions, of a platen-lifting frame comprising a rock shaft supported on the carriage in rear of the platen and having rock arms thereon extending forwardly and connected to the platen frame, a lifting spring operating through said shaft to partly counterbalance the weight of the platen frame and parts carried thereby, means for adjusting the rock shaft forwardly and rearwardly on the carriage frame to adjust the platen forwardly and rearwardly, a plate shiftably mounted on the carriage and connected with said lifting frame to be shifted forwardly and rearwardly therewith, and a link having its ends connected respectively to said shiftable plate and the platen frame to prevent the latter from tilting.

JOHN C. McLAUGHLIN.
